[57] CLAIM

The ornamental design for an electrical test probe, as shown.

DESCRIPTION

FIG. 1 is a perspective view of an electrical test probe showing our new design;

FIG. 2 is a left side elevational view thereof, the right side elevational view being a mirror image;

FIG. 3 is a top plan view thereof;

FIG. 4 is a bottom plan view thereof;

FIG. 5 is a front elevational view thereof; and,

FIG. 6 is a rear elevational view thereof.

FIG. 1

FIG. 6

FIG. 5

FIG. 2

FIG. 3

FIG. 4
